UNITED STATES PATENT OFFICE.

EDWARD BENNETT, OF OLMS TED, UTAH.

LIGHTNING-ARRESTER.

1,110,179.

Specification of Letters Patent. Patented Sept. 8, 1914.

Application filed August 26, 1908, Serial No. 450,358. Renewed February 6, 1914. Serial No. 817,055.

To all whom it may concern:

Be it known that I, EDWARD BENNETT, a citizen of the United States, residing at Olmsted, in the county of Utah, State of Utah, have invented or discovered certain new and useful Improvements in Lightning Arresters, of which improvements the following is a specification.

The invention herein described relates to certain improvements in lightning arresters used for the purpose of protecting power circuits and apparatus from the abnormal potentials resulting either from lightning disturbances or from the inherent characteristics of the system under the disturbing influence of switching operations, short circuits, grounds, and operations or accidents of a like nature.

The invention has for its object the rapid and yet gradual suppression of the dynamic current flow which always results across an arrester when the arrester functions in discharging an abnormal potential. The method by which I accomplish this result is to use in my arrester a spark gap which will be broken down at a potential a predetermined amount higher than the normal operating potential, the passage of the discharge at the abnormal potential across the arrester is accompanied by the dynamic current arc and I cause the motion of this arc along the spark gap electrodes to automatically and rapidly insert or include in the circuit predetermined and fixed resistances of a rapidly increasing value, thus reducing the volume of the current to a point where the arc is quietly suppressed.

The invention is hereinafter more fully described and claimed.

40 In the accompanying drawings, forming a part of this specification, Figure (1) illustrates diagrammatically the essential features of what I term my arrester unit; Figs. (2), (2^a) and (2^b) illustrate the details of 45 one form of arrester unit in which an air blast is used to cause the arc to travel along the electrodes more rapidly, and the inserted resistances consist of sections of a water column: Fig. (3) illustrates another 50 form of the arrester unit in which a magnetic field is used to cause the arc to move more rapidly along the electrodes, and the inserted resistances consist of sections of a resistance column formed by suitably proportioned mixtures of graphite and cement.

55 Referring to Fig. 1, (1) is a conductor

mounted, preferably, in a vertical position on insulators (2); mounted adjacent to this conductor are a number of conductors (3), which are connected to points along a suitable resistance (4), one end of which is connected to ground. The conductors (1) and (3) are, preferably, mounted inside a shaft (5) of wood or other material, preferably non-conducting. (10) represents a power station containing transformers (11), and generating apparatus (12), which it is desired to protect, (13) represents the transmission wires leading from the station.

In the practice of my invention, the conductor (1) is connected to one of the power wires (13) and the distances between the conductors (1) and (3) are so proportioned that the lowest gap (6) which is the shortest will break down at a certain predetermined potential. When this gap breaks down, the dynamo current follows and the arc so established rises along the electrodes due to the heating of the air. In rising, one end of the arc travels up the conductor (1) and the other end jumps up from conductor (8) to conductor (3) immediately above it and so on, each time inserting an additional predetermined amount of the resistance (4) in the path of the current and thereby decreasing the current.

In order to suppress the arc more rapidly, I prefer to supplement this natural draft which causes the arc to jump up from conductor to conductor by a blast up the shaft produced by any suitable means such as an aspirator at the bottom of the shaft fed by a small jet of compressed air or by a fan motor (7) or by the action of magnetic field as illustrated in Fig. 3.

Fig. 2 illustrates the details of an arrester unit as constructed for service on a 40,000 volt, three phase transmission system. The conductor (1), mounted on insulators (2), is connected to one of the wires of the transmission line. The conductors (3) which are formed of iron or copper wire project into a water column (4) which constitutes the resistance (4) described above. In the base of the water column is a metallic plate (14) which is connected to ground. The electrodes (1) and (3) are inclosed in a vertical, wooden shaft (5) at the base of which is a fan motor (7) which keeps a blast of air blowing up the shaft. In this arrester I have shown two spark gaps (6) and (8) across which the discharge may

pass: the lower gap (6) is adjusted so that its breaking down potential will be higher than that of the upper gap (8) and the cross section and length of the water column has been so proportioned that the resistance in the column from the gap (6) to ground is low, (in this particular unit 280 ohms) and the resistance from gap (8) to ground is much higher (2500 ohms). With the gap 10 (8) adjusted so that it will break down at a potential 50% above the normal operating potential and the gap (6) set so that it will break down at a potential 70% above the normal operating potential, if the potential of the line wire, due to any cause, rises to a point 50% above the normal operating potential, the gap (8) will break down and a path to ground is provided through the water column.

20 If the accumulated charge or disturbance is relatively light so that the conductivity of the path from (8) to ground is sufficient to prevent any further rise of potential, the gap (6) will not break down and the dynamic current which can flow will be greatly limited by the relatively high resistance in the discharge path. If, however, the conductivity of the path provided by the breakdown of gap (8) is not sufficient to prevent a further rise of potential, the potential will continue to rise until it becomes high enough to cause gap (6) to break down when a further rise will be prevented by the very high conductivity of the path to 30 ground so provided. In either case, the arc so established is driven up the shaft so rapidly that it is difficult to follow it with the eye, the whole operation from the passage of the discharge across the gap (6) to the time when the arc has reached the topmost conductor (3) (from which point the resistance of the water column is 11,000 ohms) consuming about one tenth of a second. Moreover the arc, in traveling up the conductor (1) and in jumping up the conductor (3), does not draw out in length and become thirty or forty feet long as in the ordinary horn arrester under similar conditions but remains quite short (about 40 six inches in length) and springs almost directly across from conductor (1) to the conductor (3) which is about opposite that end of the arc which rests on conductor (1).

45 While I have given certain resistances and proportions, I do not limit myself to these proportions. They have been mentioned for the purpose of illustrating the principle of my invention and it must be clearly understood that these proportions 55 are entirely unsuited except for a particular power system and set of conditions.

60 In Fig. 3; 1, 2, 3, 4, 6 and 14 designate the same elements as in the figures previously described. The resistance column (4) 65 is composed of cement and graphite suit-

ably proportioned to obtain the desired steps in the resistances between the projecting conductors (3) which may consist of expanded metal which has been embedded in the column during its construction. In 70 this case the conductors (3) may be dispensed with entirely and one terminal of the arc may be caused to travel directly up the face of the cement-graphite resistance column. I prefer to make the cross section 75 of the column at the base much greater than at the top to provide a greater thermal capacity for the greater amount of energy which is expended in the base and thus preclude any objectionable rise in the 80 temperature of the column when the arrester discharges the line a number of times in rapid succession. To cause the arc to rise rapidly, I combine with this arrester the choke coil which is generally used in the 85 line wires at power stations to reflect incoming surges of potential, and so locate the choke coil (9) with reference to the electrodes (1) and (3) that the magnetic field from the choke coil causes the arc to 90 travel rapidly upward.

95 While I have mentioned and specifically described certain forms of resistances and certain supplementary means of giving to the arc a rapid motion, I do not limit myself to the use of these forms or means; the use of other forms of resistance such as metallic resistances and of other means of imparting to the arc a rapid motion comes 100 within the scope of my invention.

105 The action of my arrester is entirely different from that of the well known horn gap. In the horn gap arrester it is true that the current is diminished somewhat when the arc draws out to a great length but the 110 resistance even of a ten or twenty foot air path is slight and is very uncertain. Indeed after the arc has drawn out to a great length the current is still so high that the instantaneous extinction which sometimes occurs 115 under these conditions gives rise to disturbances of greater severity than that which initially caused the horn gap to break down. On the other hand, in my arrester I do not attempt to draw out the arc but I cause the 120 motion of the arc and more particularly of the two terminals of the arc to insert or include in the circuit predetermined and fixed resistances and I proportion these resistances so that the current is cut down by 125 gradual steps to a point where the extinction of the arc produces no more effect on the system than the throwing off of a motor load.

130 I claim as my invention:

1. A lightning arrester including in combination, spaced electrodes forming a spark gap, one of said electrodes including conductors located at a plurality of spaced intervals along said electrodes and suitable re-

sistance connecting said conductors, whereby the travel of the arc along the electrodes inserts in the circuit an increasing resistance.

2. A lightning arrester including in combination, spaced electrodes forming a spark gap, one of said electrodes including projecting conductors located at a plurality of spaced intervals throughout the entire length of the electrodes, and suitable resistance connecting said conductors whereby the travel of the arc along the electrodes inserts in the circuit an increasing resistance.

3. A lightning arrester including in combination, spaced electrodes one of which is connected with a transmission line, and the other of which is connected with the ground, said electrode connected with the ground including projecting conductors located at a plurality of spaced intervals extending throughout the length of the electrode, a casing surrounding said electrode, said casing being open at the top and bottom, a fan located at the bottom of the casing for causing a circulation of air through the casing, whereby the arc is caused to travel rapidly along the electrodes.

4. A lightning arrester comprising relatively long and short diverging terminal members, a resistance connected to the shorter terminal member, and a plurality of overlapping conductors that are connected at intervals to the resistance and constitute an extension of the shorter terminal member.

5. A lightning arrester comprising rela-

tively long and short diverging terminal members, a resistance connected to the shorter terminal member, a plurality of over-lapping conductors that are connected at intervals to the resistance and constitute an extension of the shorter terminal member, said conductors being separated from the longer terminal member by air spaces, the width of which differ as the distance between the same and the shorter terminal member increases.

6. A lightning arrester comprising two diverging terminal members of unequal length, a series of over-lapping conductors that constitute an extension of the shorter terminal members, and a single high-resistance support for said over-lapping conductors.

7. A lightning arrester comprising terminal members one of which consists of a plurality of over-lapping conductors and a single high-resistance support for said conductors.

8. A lightning arrester comprising a pair of terminal members one of which consists of a refractory high-resistance member and a series of over-lapping conducting members supported thereby.

In testimony whereof I have hereunto subscribed my name this 29th day of May, 1908.

EDWARD BENNETT.
